(57) **CLAIM**

The ornamental design for a camera as shown and described.

DESCRIPTION

FIG. 1 is a front, top isometric view of a camera.

FIG. 2 is a back, bottom isometric view thereof.

FIG. 3 is a front side elevation view thereof.

FIG. 4 is a back side elevation view thereof.

FIG. 5 right side elevation view thereof.

FIG. 6 is a left side elevation view thereof.

FIG. 7 is a top side plan view thereof.

FIG. 8 is a bottom side plan view thereof.

FIG. 9 is a front, top isometric view of the camera of FIG. 1 with the battery compartment open, it being understood that all other surfaces are the same as in the other views.

FIG. 10 is a back, bottom isometric view thereof.

FIG. 11 is a front side elevation view thereof.

FIG. 12 is a back side elevation view thereof.

FIG. 13 right side elevation view thereof.

FIG. 14 is a left side elevation view thereof.

FIG. 15 is a top side plan view thereof.

FIG. 16 is a bottom side plan view thereof.

FIG. 17 is a front, top isometric view of a camera.

FIG. 18 is a back, bottom isometric view thereof.

FIG. 19 is a front side elevation view thereof.

FIG. 20 is a back side elevation view thereof.

FIG. 21 right side elevation view thereof.

FIG. 22 is a left side elevation view thereof.

FIG. 23 is a top side plan view thereof.

FIG. 24 is a bottom side plan view thereof.

FIG. 25 is a front, top isometric view of the camera of FIG. 17 with the battery compartment open, it being understood that all other surfaces are the same as in the other views.

FIG. 26 is a back, bottom isometric view thereof.

FIG. 27 is a front side elevation view thereof.

FIG. 28 is a back side elevation view thereof.

FIG. 29 right side elevation view thereof.

FIG. 30 is a left side elevation view thereof.

(Continued)

FIG. 31 is a top side plan view thereof.

FIG. 32 is a bottom side plan view thereof.

FIG. 33 is a cross-section view taken along line 33-33 of FIG. 28.

FIG. 34 is a cross-section view taken along line 34-34 of FIG. 28.

FIG. 35 is a cross-section view taken along line 35-35 of FIG. 28; and,

FIG. 36 is a cross-section view taken along line 36-36 of FIG. 28.

The features shown in broken lines in the drawings depict environmental subject matter and unclaimed borders and form no part of the claimed design.

1 Claim, 36 Drawing Sheets
